UNITED STATES PATENT OFFICE.

CHAUNCEY D. PEASE, OF NEW YORK, N. Y.

ORNAMENTAL GLASS PANEL.

SPECIFICATION forming part of Letters Patent No. 334,677, dated January 19, 1886.

Application filed November 12, 1885. Serial No. 182,606. (No model.)

To all whom it may concern:

Be it known that I, CHAUNCEY D. PEASE, of New York city, in the county of New York, and in the State of New York, have invented 5 certain new and useful Improvements in Ornamental Glass Panels; and I do hereby declare that the following is a full, clear, and exact description thereof, reference being had to the accompanying drawings, in which—

10 Figure 1 shows a front view of the panel with its frame; Fig. 2, a section of the same on line $x\ x$ of Fig. 1; Fig. 3, a view of the same from the rear side with portions removed or broken away to show the construction more 15 clearly; Fig. 4, a view of a modified form of spring to be used in making up my panel, and Fig. 5 a detail view showing a modification of the means for holding the glass in the frame.

Letters of like name and kind refer to like 20 parts in each of the figures.

The object of my invention is to provide an improved glass panel with frame or casing; and to this end my invention consists in the construction, arrangement, and combination 25 of parts, as hereinafter set forth, and more particularly pointed out in the claims.

In the drawings, A designates the panel casing or frame, and B the sheet of glass forming the main portion of the panel. This glass 30 I prefer to have as shown in the drawings. It is made of dark purple flashed glass, the flashed surface being on the front side of a clear layer of glass, and being cut away so as to leave a raised design of dark color on a clear-glass 35 surface or backing. The purple flashed glass is preferred, because the design then appears like rosewood fret-work. The glass best suited for this purpose has an unusually deep flashing, so that the design stands out clearly 40 and boldly, and at a short distance cannot be distinguished from the finest and most delicate fret-work. Obviously the design can be made much finer and more delicate than if wood were used, and is permanent and not 45 liable to crack or break with the heat, and always has the highest polish, not subject to injury or deterioration by time or alternations of heat and cold.

The frame A is preferably made of a solid 50 piece, with the panel-opening C of the desired shape cut therein. With this construction the grain of the wood all runs the same

way, and joints at the corners are avoided. The glass pane is made larger than the opening C, so as to overlap its edges on all sides, 55 as shown in the drawings.

On the back of frame A, close up against the ends of the glass, are nailed or otherwise fastened the strips D D—one at each end—of a thickness substantially equal to that of the 60 glass, or, if desired, a trifle less. Between the overlapping edges of the glass and the back of the frame A, around the opening, I place a thin strip of broadcloth or other cloth. I contemplate using, instead of cloth, for this 65 purpose, any soft or semi-elastic substance—as, for instance, paper, or elastic substance, as rubber.

I do not limit myself to any particular substance; but whatever is used it should be soft 70 and capable of yielding a little as the glass is pressed and fastened down in place, as hereinafter described.

To the back of frame A, a short distance from the upper and lower edges of the glass, 75 are fastened the strips D' D', like strips D D. Between each of these strips D' D' and the adjacent edge of the glass are placed several blocks of rubber, d d d. Any desired number 80 of these blocks can of course be used. Similar blocks can be placed, if desired, between the end edges of the glass and the strips D D; but such where, as shown in the drawings, the grain runs parallel to the top and bottom edges of the glass are not necessary. The 85 blocks d d are to take up or compensate for the unequal expansion and contraction of the glass.

As is well known, there is little or no contraction of the wood in a direction parallel to 90 the grain thereof, but only in a direction at right angles to the grain. The spring-blocks d d are then only necessary on the sides parallel to the grain—that is, in the drawings the top and bottom sides of the glass. Without 95 these spring-blocks, when the wood contracted, as it is bound to do in time, the frame would open at the sides. With the blocks any unequal expansion or contraction of the wood and glass will always be taken up. 100

Instead of rubber spring-blocks, as described, I contemplate also using metal springs for the same purpose, said springs being formed, as shown at E in Fig. 4, of a bow-

shaped strip of metal with its ends rounded or bent, as shown, so as to make good bearing-surfaces at *e e*. Over the back of the glass a piece of cloth, *F*, preferably of satin, is laid and pasted or otherwise fastened at its edges to strips *D D' D'*. This cloth backing is best made of material having a color contrasting with the raised design on the front of the glass. Over the cloth is placed a board, *G*, which is then fastened down in place by means of screws *g g*, or otherwise, as desired. When this board backing *G* is fastened down in place, the glass sheet *B* will be firmly held between the strip of cloth on its front side and the cloth *F* at its back, so that there is no chance for rattling where the panel is used on a piano, for which use it is especially intended. The spring-blocks or springs between strips *D' D'* and the edges of the glass would alone tend to prevent rattling, but with these and with cloth or yielding material between the casing and glass and the latter and the back board rattling is impossible.

Of course, instead of cloth between the glass and the back board, *G*, a layer of any other soft material, or semi-elastic or elastic stuff, can be used of any desired color; but I prefer the cloth, as described.

Instead of having the design on the front of the glass the sheet can be turned so as to bring the design on the back; but this is not so good, as said design is not then so clear, and of course does not stand out like fret or carved work.

35 Instead of using the strips shown and described for holding the glass, the frame could obviously be rabbeted to receive the sides and edges of the glass sheet without departure from my invention.

40 I do not claim herein the glass panel proper with its raised design in color, and having a suitable backing, as shown and described, and covered by the claims in my United States Patent No. 329,771, November 3, 1885.

45 Having thus described my invention, what I claim is—

1. In combination with a sheet of glass, the frame having a suitable panel-opening, cloth between the glass and the frame, a sheet or 50 piece of cloth behind the glass, and a suitable backing-board fastened to the frame beyond the edges of the glass, substantially as and for the purpose described.

2. In an ornamental panel, in combination with the sheet of glass, the frame provided with a suitable panel-opening, and adapted to receive and hold the glass sheet at its edges, springs bearing against the edges of the sheet,

substantially as and for the purpose described.

60

3. In combination with the sheet of glass for an ornamental panel, the frame provided on its back with strips to hold the glass from movement with relation to the panel-opening, and springs or cushions between the strips and the edges of the glass, substantially as and for the purpose described.

65

4. In combination with the panel-frame made of one piece of wood, and provided with a suitable panel-opening, the glass sheet or plate overlapping the rear edges of the opening, means, substantially as described, for engaging and holding the edges of the glass which run across the grain of the wood, and springs 70 pressed against and holding the other sides or 75 edges of the glass, substantially as and for the purpose described.

75

5. In combination with the sheet of glass having on its front face the raised ornamental design in flashed glass, the panel-frame made 80 of one piece of wood, with the panel-opening cut therein, suitable shoulders on or attached to the back of the frame, adapted to engage the edges of the glass which run across the grain of the wood of the frame, and spring-blocks or cushions engaging and holding the 85 sides or edges of the glass running with the grain, substantially as and for the purpose described.

85

6. In combination with the ornamental sheet 90 of glass, the panel-frame made of one piece of wood with the panel-opening cut therein, a packing of soft material between the frame and the front side of the glass, strips attached to the frame and engaging the sides of the glass 95 sheet which run across the grain of the panel-strips on the frame parallel to the other sides of the sheet, and spring-cushions between these latter strips and the sides of the glass, substantially as and for the purpose described.

100

7. In combination with the panel-frame *A*, provided with panel-opening *C*, the sheet of glass *B*, the cloth between the glass and the frame, the strips *D D* and *D' D'*, the rubber blocks *d d* between the sides of the glass, and 105 strips *D' D'*, the cloth back of the glass fastened to the strips and the board backing *G*, all substantially as and for the purpose described.

105

In testimony that I claim the foregoing I have hereunto set my hand this 2d day of October, A. D. 1885.

CHAUNCEY D. PEASE.
